Fig. 1

FIG. 1 is a front elevational view of a light emitting gas discharge matrix display panel showing our new design, the rear being identical to the front shown except that plate nearest the viewer becomes the most remote from said viewer and vice versa;

FIG. 2 is an elevational view taken from one side thereof, the opposite side being a mirror image of the side shown; and

FIG. 3 is a bottom plan view thereof, the top being a mirror image of the bottom shown.

This is a continuation-in-part of design application Ser. No. 191,960, filed Oct. 22, 1971, now Design Pat. No. D. 230,984, issued Mar. 26, 1974.

We claim:

The ornamental design for a light emitting gas discharge matrix display panel, as shown and described.
